UNITED STATES PATENT OFFICE.

WILLIAM J. DOYLE AND JUSTUS J. WOLLENHAUPT, OF CINCINNATI, OHIO, ASSIGNEES
TO THE MONITOR STOVE & RANGE COMPANY, OF CINCINNATI, OHIO, A CORPOR-
ATION OF OHIO.

FURNACE.

1,133,242.

Specification of Letters Patent. Patented Mar. 23, 1915.

Application filed March 23, 1914. Serial No. 826,801.

To all whom it may concern:

Be it known that we, WILLIAM J. DOYLE and JUSTUS J. WOLLENHAUPT, citizens of the United States, and residing at Cincinnati, in the county of Hamilton and State of Ohio, have invented a new and useful Furnace, of which the following specification is a full disclosure.

The invention relates to furnaces of the hot-air conductor type, in which cold-air and hot-air ducts have coincident terminals above the heater.

An object of the invention is to provide a furnace in which the heater is surrounded by two chambers intercommunicable at the base, the one an outer, providing a cold-air chamber, and the second an inner providing a hot-air chamber. The casing forming the outer member has a rigid heater face plate contiguous with its circumference providing a terminal for the projecting heater passages and supports the doors therefor. A second casing concentrically within the first, forms the inner or hot air chamber, has an offset portion connecting with the face plate of the outer casing, providing an area-way for the projecting heater passages, with the base edge of said casing superposed from the furnace base for offering communication between said cylinders.

There are various other objects and features of our invention some of which relate to structural details, all of which will be more fully defined in detail in the following description of the annexed drawings illustrating a preferred embodiment of the invention, and forming a part of this disclosure, and in such drawings like characters of reference denote corresponding parts throughout the several views of which:—

Figure 1 is a central vertical section through our improved furnace, illustrating the heater in elevation. Fig. 2 is a section on line 2—2, Fig. 1. Figs. 3, 4 and 5 are perspective views illustrating details of the furnace, namely the front face plate, inner casing and top plate connecting the inner casing and face plate. Fig. 6 is a section on line 6—6, Fig. 1. Fig. 7 is an enlarged section on line 7—7, Fig. 6. Fig. 8 is an enlarged detailed sectional view of the plate connecting the upper portion of the face plate with the inner casing.

As illustrated the furnace is of the well

known type wherein the heater is surrounded by casings constituting two chambers, the one a hot-air chamber for conducting the hot air upwardly, and the second a cold-air chamber for conducting the cold atmosphere downwardly, communicating with the hot-air chamber at the base thereof.

The heater may be of any well known construction and design, comprising the ash-pit 1, fire-box 2, combustion chamber 3 and hot-air dome 4, separably united in a manner well known in the art and commonly practised.

The heater in the disclosure herein is possessed of a distinguishing feature, in that the heater dome or radiator 4, has its axis disposed eccentrically to the axis of the fire-box and combustion chamber, the purpose of which is to position the ash-pit, fire-box and combustion chamber forwardly relative to the surrounding casings, so as to reduce the length of the passages or hoppers 5 and 6, communicating respectively with the ash-pit and combustion chamber. This places a portion of the heater, preferably the major portion thereof, eccentrically within the surrounding chambers, and the hot-air dome or radiator concentrically within the same, presenting a circumferential exterior and provides a greater cubic area for the hot-air chamber within the given circumferential area of the furnace. An apertured cast face plate 8 surrounds and is secured to the extremities of the passages 5 and 6, and provides a rigid front wall portion to which the casings surrounding the heater are secured, and contiguous with the outer casing. The face plate supports the doors for the passages and other fittings for the various ports leading into the furnace for clean-out or regulating purposes.

The heater is supported upon a cast base 9 corresponding in outline with that of the ash-pit for which it serves as a bottom.

10 represents a split ring base for supporting the outer casing, which surrounds the heater with its ends oppositely secured to the base member 9 by means of the lugs 11 and 12 respectively oppositely projecting from said members for receiving the fastening bolts. The ring member 10 is preferably of sectional form with the sections abuttingly united by the T-links 13 secured to lugs projecting inwardly and adjacently

from the sections. The T-links each project in diametric planes with the heater, and are secured to relatively projected lugs integral with the base member 9. Thus the 5 ring base member occupies a relatively spaced position from the base member 9, and said members as a unit present a circumferential outline.

A hot-air chamber 17 surrounds the 10 heater and is formed by the circular sheet metal casing 18 having its end provided with radial flanges 19, 20, terminating in the fastening margins 21, 22, respectively, for securing the same to the face plate 8, 15 providing an offset in the chamber 17 as an area-way for the hoppers or passages of the heater connecting with the face plate. The casing terminates at its lower portion approximately at a plane coincident with the 20 top wall of the ash-hopper or passage, with the lower margin of the casing reinforced by a beaded binding ring 23, having a bead 23' engaged with the edge of the casing. The ends of the binding ring are secured to 25 the side walls of the ash-hopper. The casing beyond the front face plate is supported by the standards 24 resting and secured upon the links 13. It will be observed that the base of the chamber 17 is open and circumferentially in communication with the 30 cold-air chamber 25 surrounding the casing 18 and formed by the sheet metal casing 26 having its ends secured to the face plate 8 coincidentally with the fastening margins 35 21, 22, respectively, of the inner casing 18.

27 represents a cast plate having front and rear circular margins, the front margin abuttingly engaged against the inner surface of the face plate 8 and secured thereto 40 by a bolt engaging through the offsets 27a. The opposite or rear margin comprises a flange 28 projected upwardly from the plate 27 and secured to the lower edge of the top casing section 30, which joins the top wall 45 33 of the offset portion of chamber 17. The casing section 30 has a reduced diameter portion providing a hot-air conductor 29 engaging with the register plate 32 which seats into or upon the floor above the furnace.

50 The casing section 30 may be united to the main portion of the casing 18 by a beaded ring or in any well-known manner. The outer casing is also provided with a top casing section 34, terminating in conduit or conductor 35, surrounding the conductor 29, and engaged with the register plate 32, providing a cold-air duct circumferentially around the hot-air duct. The cold air is drawn downwardly through the chamber 25, and thence upwardly around the heater to be heated in the chamber 17 and discharged through the conductor 29. The register plate 32 represents a grating having a flange 32' projecting from its lower surface to telescopically engage with the cold-air con-

ductor 35, with margins beyond the flange supporting the grating upon the floor above the furnace. A second flange projects from the lower surface of the grating 32 as divisional of the hot and cold-air passages 70 which telescopically engage with the hot-air conductor 29. The grating, therefore, is of integral construction, serving for both conductors.

Having described our invention, we 75 claim:

1. A furnace of the character described combining a heater having passages projected therefrom, two concentric circumferential casings surrounding said heater providing two chambers communicating at their base, the outer casing having a rigid heater passage terminal plate circumferentially continuous therewith and the inner casing having an offset portion united to the margins 80 of said plate providing an area-way for said heater passages.

2. A furnace of the character described combining a heater having passages projected from its various compartments, two concentric casings surrounding said heater, providing two chambers communicating at their base, said casings at their upper portions forming conductor passages for the chambers respectively, one to admit cold air into 95 the outer chamber and the second for discharging the heated air from the inner chamber, the outer casing having a heater face plate circumferentially continuous therewith as a terminal for said heater passages and the inner casing having an offset portion united to the margins of the face plate providing an area-way for said heater 100 passages.

3. A furnace of the character described 105 combining a heater having passages projected therefrom, a casing surrounding said heater having a rigid passage terminal portion continuous with the circumference of said casing, a second casing within said first 110 casing divisional of two chambers communicative at their base, said second casing having an offset portion connecting with said rigid portion of said first casing providing an area-way for said heater passages. 115

4. A furnace of the character described combining a sectional heater comprising an ash pit, fire-box and combustion chamber substantially coaxial, and a register dome axially eccentric to the aforesaid sections, 120 two concentric circumferential casings surrounding said heater, forming two chambers, an inner and an outer, intercommunicable at their base, the outer providing a terminal for the passages projecting from the 125 heater, and the inner having an offset portion secured to the outer providing an area-way for said passages.

5. A furnace of the character described combining a sectional heater comprising an 130

ash-pit, fire-box and combustion chamber substantially coaxial, and a register dome axially eccentric to the aforesaid sections, two concentric circumferential casings surrounding said heater, forming two chambers, an inner and an outer, intercommunicable at their base, the outer providing a terminal for the passages projecting from the heater, and the inner having an offset portion secured to the outer providing an area-way for said passages, and a register grat-

ing supported above said chambers divisionally connected with said casings.

In witness whereof, we hereunto subscribe our names, as attested by the two subscribing witnesses.

WM. J. DOYLE.
J. J. WOLLENHAUPT.
